UNITED STATES PATENT OFFICE.

JOHN NUEBLING, OF EVANSVILLE, INDIANA, ASSIGNOR TO HIMSELF AND
THOMAS J. GROVES, OF SAME PLACE.

INK-FOUNTAIN FOR CHROMATIC-PRINTING MACHINES.

SPECIFICATION forming part of Letters Patent No. 358,473, dated March 1, 1887.

Application filed February 9, 1886. Serial No. 191,308. (No model.)

To all whom it may concern:

Be it known that I, JOHN NUEBLING, a citizen of the United States, residing at Evansville, in the county of Vanderburg, State of Indiana, have invented certain new and useful Improvements in Ink-Fountains for Chromatic-Printing Machines, of which the following is a specification, reference being had therein to the accompanying drawings.

10 This invention relates to improvements in inking-founts for printing establishments, and has for its object to provide an inking apparatus to be used with printing-presses in which several different colors may be held and used 15 at the same time. This object is attained by the mechanism illustrated in the accompanying drawings, forming a part of this specification, in which—

Figure 1 is a plan from which the reservoir 20 has been removed. Fig. 2 is a detached plan view of the reservoir. Fig. 3 is a transverse sectional view. Fig. 4 is a detached view of an ink-separator. Fig. 5 is a detached end view of the reservoir. Fig. 6 is a rear view of 25 one of the lower corners of the fount, the remainder being broken away; Fig. 7, a side elevation of the fount; and Fig. 8, a plan view of portions of the bottom of the fount, showing the spring for separating them in position.

30 The letter A indicates the reservoir, which is attached to the frame or body of the machine A' by the screws G and by the handles a, which are held down at each end of the machine by the screw-eyes b. A strip, F, of rubber, is attached to the bottom of the reservoir, 35 to prevent the flowing of the ink.

B is a piece of metal extending across the machine, which is attached to the piece H (forming part of the bottom or base of the 40 frame A') by means of pins d, which are intended to prevent the piece B from slipping.

B' are thumb-screws which pass through the piece B and enter the keys C, and serve the purpose to adjust the keys C and bring them 45 close up to the ink-roller J or to remove them farther therefrom. These keys C rest upon the bottom H' of the frame A' and slide freely thereon during the time of adjustment.

The piece H is attached to the bottom H' by

means of the screw h, and is also provided 50 with tongues h', which enter grooves h" near the bottom of the frame A'. This construction permits the piece H to be brought closer to or to be removed farther from the bottom H', as there is a narrow space between the two, in 55 which are located one or more springs, j, which are attached to the bottom H' and bear against the piece H and tend to force them apart.

The letter D indicates the ink-separators, which are intended to act as partitions to divide the ink-reservoir up into several receptacles for chromatic work, and are adjustable to different distances apart, having a recess cut out of the top covered by a plate, e, having a thumb-nut, e'. The recess is intended to 65 receive a bar, E, upon which the partitions D slide, so that they may be placed different distances apart and be securely held by means of the thumb-nut e'. The faces of the partitions or separators are lined with rubber, d', for the 70 purpose of confining the inks.

J is the ink-roller, having bearings in the frame A'.

The frame A' and base or bottom H' may consist of a single casting or of several pieces 75 connected to each other in any suitable manner. The keys C are used for the purpose of regulating the flow of the inks to the roller J. By removing the screw h the piece H may be detached, together with the bar B, and also the 80 whole of the keys C.

Having described my invention, what I desire to secure by Letters Patent, and claim, is—

1. In an ink-fount, the combination, with the ink-reservoir A, of the bars E and the partitions D, having plates e and thumb-screws e', whereby the partitions may be adjusted and held at any set position.

2. In an ink-fount, the combination of the frame A', the base H', the piece H, the screws, 90 and the spring between said base and said piece, the keys C, and the thumb-screws B'.

In testimony whereof I affix my signature in presence of two witnesses.

JOHN NUEBLING.
